COFFEE MAKER

Edward J. Ruhnke, Chicago, Ill., assignor to Hill-Shaw
Co., Chicago, Ill., a corporation of Illinois

Filed Jan. 23, 1961, Ser. No. 63,645

Term of patent 14 years

(Cl. D2—3)

The dominant features of my design reside in the portions shown in full lines, said portions being characterized by the upwardly and outwardly extending central burner unit in combination with the stepped burner units on the side having the upstanding flanges at the rear as shown.

The dispensing bowls are included for purposes of illustration only.

I claim:

The ornamental design for a coffee maker, substantially as shown and described.
